(57) **CLAIM**

The ornamental design for a handle assembly for a portable x-ray device, as shown and described.

DESCRIPTION

FIG. 1 is a perspective view of a handle assembly for a portable x-ray device.

FIG. 2 is a rear view of the handle assembly design shown in FIG. 1.

FIG. 3 is a front view of the handle assembly design shown in FIG. 1.

FIG. 4 is a bottom view of the handle assembly design shown in FIG. 1.

FIG. 5 is a top view of the handle assembly design shown in FIG. 1.

FIG. 6 is a side view of the handle assembly design shown in FIG. 1; and,

FIG. 7 is a side view of the handle assembly design shown in FIG. 1, opposite of the side shown in FIG. 6.

The broken lines represent environmental subject matter and form no part of the claimed design.

1 Claim, 5 Drawing Sheets
